UNITED STATES PATENT OFFICE.

EDWIN L. WHITLOCK AND JAMES MADISON, OF NEW YORK, N. Y.

DESIGN FOR A DOLL.

Application filed December 22, 1923. Serial No. 8,121. Term of patent 3½ years.

To all whom it may concern:

Be it known that we, EDWIN L. WHITLOCK and JAMES MADISON, citizens of the United States, and residents of the city of New York, county and State of New York (whose post-office addresses are, respectively, No. 286 Fifth Avenue, New York, N. Y., and 1493 Broadway, New York, N. Y.), have invented a new, original, and ornamental Design for a Doll, of which the following is a specification, reference being had to the accompanying drawing, forming part thereof.

Figure 1 is a side view while Figure 2 is a front view of a doll showing our new design.

We claim:

The ornamental design for a doll substantially as shown.

EDWIN L. WHITLOCK.
JAMES MADISON.
